UNITED STATES PATENT OFFICE.

ALEXANDER E. BROWN, OF CLEVELAND, OHIO.

BLAST-FURNACE FILLING CONTRIVANCE.

SPECIFICATION forming part of Letters Patent No. 432,788, dated July 22, 1890.

Application filed March 7, 1889. Serial No. 302,374. (No model.)

To all whom it may concern:

Be it known that I, ALEXANDER E. BROWN, of Cleveland, in the county of Cuyahoga and State of Ohio, have invented a new and useful Improvement in Blast-Furnace Filling Contrivances; and I do hereby declare that the following is a full, clear, and exact description thereof, reference being had to the accompanying drawings, making part of this specification.

There has always been, previous to my invention, more or less serious trouble or difficulty in the way of running blast-furnaces with the best practical results possible on account of the imperfect manner of filling the furnace, it having been practically impossible heretofore to always have the stock (the ore, fuel, and flux) properly distributed on the top surface of the mass composing the contents of the furnace.

To provide a means by which, in filling the furnace, (either through the medium of automatically-working skip-cars or by the use of barrows manipulated by hand,) the stock fed to the furnace must inevitably be supplied to it and distributed therein in a predetermined manner, is the main object of my invention, which to this end may be said to consist, essentially, in combining with the furnace-top some suitable automatically-operated device through an opening or openings in which the stock must pass into the furnace, but which, either by an arbitrary rotary movement of said device, (if it has a single opening,) or by a predetermined manner of opening successively each of its ingress-orifices, (if it have more than one opening,) insures the depositing of the successive charges of stock brought to the furnace-top at such points and in a manner such that the stock will be properly distributed in a predetermined manner over the top surface of the mass of materials contained within the furnace, all as will be hereinafter more fully explained, and as will be more particularly pointed out and concisely defined in the claims of this specification.

To enable those skilled in the art to which my invention relates to understand and practice the same, either in the form or forms in

which I have herein shown my improvement carried into effect or under some modification not herein shown, I will now proceed to more fully describe it, referring by letters to the accompanying drawings, which form part of this specification, and in which I have shown my said invention carried out in two forms in which I have so far successively practiced it, in one of which the construction is specially adapted to a furnace designed to have the filling done by hand-labor with ordinary wheelbarrows, and in the other of which the structure is particularly designed for use in a case in which the stock is elevated to and dumped into the furnace-top opening by automatically-worked skip-cars which travel on an inclined track leading from the source of stock-supply to the furnace-top.

As in each of the two forms of contrivance shown the details of construction vary somewhat (as the circumstances require) from those of the other, though the same principle is involved in both, it will be better to separately describe the said two forms of apparatus. I will therefore first describe my invention with special reference to the form of contrivance shown on Sheet 1 of the drawings, in which the stock is fed or filled into the furnace by hand-labor, and then explain the construction seen at Sheet 2, in which there is an automatic skip-car mechanism for bringing the stock up to the furnace-top.

As the two forms of apparatus shown have certain parts in common, I have in the respective drawings used the same reference-letters for these parts.

Referring now only to Sheet 1, Figure 1 is a vertical section of the upper portion of an ordinary blast-furnace provided with the usual elevator, bridge, and top platform for filling by hand-labor, but having my invention or improvement for insuring a perfect distribution of the stock dumped into the furnace-top from the wheelbarrows of the operatives. Fig. 2 is a plan view of the furnace-top, showing the overhead shafting in dotted lines, and in both these figures the same parts are marked with the same letters. Fig. 3 is an enlarged detail view.

A is the upper part of the furnace, provided in the usual manner with a platform B for the men to travel on, a lateral extension of which communicates with the upper part of 5 the elevator structure D, and is supported by suitable trusses or beams C, extending from said structure to the top of the furnace, all in a manner well known. The furnace-top is provided with a hopper d and a bell F, the 10 latter being raised and lowered through the medium of the rod a, lever b, (fulcrumed in the standard c,) and suitable operating mechanism, all after any one of the known and approved modes.

15 E are the elevator cages or cars for bringing up the furnace-feeders and the charges of stock carried in the wheelbarrows, one of which I have shown at P as having its contents being dumped into the furnace by the 20 operative who handles it.

H is a shaft, which in the case shown carries at one end the rope-wheel J of the elevator-cages and which at the other end is journaled in a suitable box n, mounted on the 25 apex of a metallic frame G. This shaft, which is rotated, of course, alternately in opposite directions, has keyed on the end last referred to a bevel-gear K, which engages with two horizontally-located bevel-wheels L 30 and M, each of which is mounted to turn freely on the vertical shaft l, and which acts alternately to drive the said shaft always in one direction of rotation. Said shaft l is stepped at its lower end in a suitable bearing-box r and has an upper journal-box at m, which is secured to a cross-piece of the A-frame G, as shown, and on the lower end of this shaft is a small chain-wheel or sprocket-pinion k, which operates to drive the link 35 40 belt or chain j, which is banded from said pinion, onto the rim-like chain-wheel i of a rotary cover or turn-table e, the operation and function of which will be presently explained.

As already remarked, the rotatory movements of the drive-gear K in first one and then another direction (as first one and then the other of the elevator-cars ascends) causes each of the bevel-gears L M to rotate in first one and then the other direction, (see Fig. 45 50 55 60 65 3;) but as each of these gears is mounted to turn on the shaft l, but is indirectly connected with it through the medium of a pawl o, pivoted thereto at one end and having its other end in engagement with the teeth of a ratchet-wheel p, that is fast on said shaft, it follows that the two gears L and M actuate the shaft only at such times as they will operate to turn said shaft in a given direction of rotation. This periodical or intermittent rotation of said 65 shaft causes the turn-table or cover e to be rotated always in the direction indicated by the arrow at Fig. 2, and at each movement of said cover e its filling, opening, or ingress aperture f is shifted to a new position, as indicated by the various positions of said aperture drawn in dotted lines at Fig. 2 and num-

bered from 2 to 6, inclusive. The said turn-table e is preferably made with a circular slightly-depending track on its under surface, which rests and rides upon a series of small 70 wheels or anti-friction rollers g, (see Fig. 1,) the spindles or axes of which rollers are mounted suitably in bearings formed in a series of stand-like projections on the inner side of the hopper d, all as clearly shown, and 75 at each movement of travel of an elevator-car (that brings up a wheelbarrow load or charge of stock) the drive-shaft H, through the system of gears already explained, causes the said turn-table to make (in the case shown) 80 one-sixth of a revolution.

As is well known to those skilled in the art, there is always a great accumulation on all the parts of any mechanism at the top of a furnace of coal-dust, the presence of which 85 operates to impede the action of the working or contacting parts of any mechanism employed. A great advantage is therefore gained by mounting the turn-table or rotary top plate of the furnace, so that the track is 90 uppermost and the wheels underneath the track, as hereinbefore shown and described. Of course it is not material, so far as this part of my improvement is concerned, that the track and wheels be located in precisely the 95 manner shown in the drawings, so long as a circular track be employed that travels on top of a series of wheels, which latter, by reason of their circular shape and rotatory motion, are not capable of retaining on their 100 contacting surfaces the dirt or dust which would accumulate on the surface of the circular track were the latter arranged as usual, with its contacting surface upward, and were the wheels mounted on or attached to the 105 turn-table.

In the operation of the contrivance so far described (and shown in Sheet 1 of the drawings) the operative or filler attendant dumps his wheelbarrow-loads of stock through the 110 opening f of the turn-table e onto the bell F in the manner clearly shown at Fig. 1, and by the subsequent descent of the bell F (in the usual manner) the stock thus deposited on the bell is permitted to descend into the 115 furnace. After having dumped in the first barrow-load, and by the time another wheelbarrow-load of stock shall have been elevated to the level of the platform B, the turn-table e will have been rotated the sixth part of 120 a revolution, so as to bring the aperture into the position in which it is drawn in dotted lines at 2, Fig. 2, and the operative will then be obliged to wheel his barrow or charge of stock to a different point in order 125 to dump it into or through the same aperture f in its new position, and so on, so long as the furnace may be run, will each successive charge have to be dumped through the same aperture f in its different successive 130 positions, the result of which of course is that the successive charges are lowered into the

furnace (whenever the bell may be lowered) in such manner that the stock will be distributed over the entire top surface of the mass of material contained within the furnace in a proper and predetermined manner, and so that this proper distribution of the six charges is repeated as to every successive series of six charges. It will be seen that since the charges in position of the aperture *f* are automatically 5 and inevitably produced synchronously with the delivery at the top of the furnace of the successive charges of stock to be dumped (by hand-labor in this instance) into the furnace the charges thus brought up must be put in 10 so as to fill the furnace in the desired manner. There is nothing left to the judgment of the operatives. They cannot exercise any discretion, and the automatic movements of the filling-in aperture *f* necessitate or enforce 15 the filling of the furnace in accordance with the described mode of operation of and with the result due to the use of the automatic contrivance described.

The details of construction of the apparatus 20 shown may be varied in many particulars without departing from the spirit of my invention, the gist of which lies in a filling-aperture which enforces the depositing of the charges either on the bell or within the furnace-top when no bell is used at constantly-changing localities and so as to effect always 25 a proper predetermined distribution of the material. I deem the particular form of turn-table shown, (when one may be used,) with a track on the under surface resting on a series 30 of wheels *g*, the axes of which are mounted in fixed bearing, not only a preferable, but the most desirable form, since there can then be no accumulation of dust and dirt on the 35 track-surface to impede the easy action of the moving parts, and of course the wheels, from their shape, are not liable to get clogged by any collection of dirt on their peripheries.

It is not material that the particular manner or means shown for imparting the proper 40 movements to the turn-table be used in carrying out my invention, as any other mechanism and any source of motive power will answer the purpose so long as the proper and 45 arbitrary shifting movements of the filling-in aperture *f* be effected synchronously with the times of delivery at the furnace-top of the charges of stock to be filled in.

Indeed, so far as the principle of my invention 50 and its novel effects may be concerned, a contrivance might possibly be made in which, in lieu of the revolving cover *e* with its aperture *f*, some sort of stationary cover might be employed, provided with a series of 55 trap-doors, which might be automatically opened and closed successively by some suitable mechanism, so as to produce substantially the same effect as accomplished by the apparatus shown and so far described.

60 Referring now to Sheet 2 of the drawings, in which I have shown my invention as ap-

plied to a furnace provided with a wholly mechanical and automatic stock feeding or filling contrivance, Fig. 4 is a partial vertical section of such a contrivance with my invention applied thereto. Fig. 5 is a side view of the apparatus seen at Fig. 1, looking in the direction indicated by the arrow. Fig. 6 is a diagrammatical plan of the furnace-top and filling-hopper. Fig. 7 is a detail plan view, 70 on an enlarged scale, of some of the working parts; and Fig. 8 is a side view of the parts seen at Fig. 6 and on the same scale.

In all the figures of this sheet the same parts are indicated by the same letters. 80

A is the upper portion of the furnace, and *d* the usual hopper, having combined with it the ordinary bell *F*, the latter adapted to be raised and lowered through the medium of its rod *a*, the lever *b*, (pivoted in a part *c*), and 85 suitable operating mechanism, all in a manner well known.

B is a sort of duplex **A**-frame, mounted over the furnace, with the apices of its parts connected by a cross-beam *C*, and having one 90 side or set of the legs extended obliquely down to the stock-house or the level at which the skip-cars *D*, which travel on a track laid on said legs of said frame-work, are filled or supplied with the stock to fill the furnace, all in 95 a well-known and approved manner.

The construction and mode of operation of the cars *D*, the wheels or trucks *e* and *f* of which travel on the peculiarly-arranged tracks *a*² and in such manner that when the cars 100 have been drawn up by the cable *f*² to the position seen in the drawings they will automatically dump their contents into the opening of the furnace top, are well known by practical operation in public, and therefore 105 need not be herein described.

H is a rotatory feed-hopper, which, as shown, is formed with a chute-like extension *t* at its lower or discharge end, and is arranged centrally over the furnace and with its egress 110 end inserted within a central opening in the top plate of the furnace, all in such manner as to bring the lower end of its discharge chute or nozzle *t* a little to one side of or relatively eccentric to the apex of the bell *F*, so that, as 115 clearly shown at Fig. 3, whenever the contents of one of the skip-cars *D* shall be discharged into the said feed-hopper the charge of stock will freely descend through the latter and will be deposited on one side of the 120 bell, as illustrated at *x*. (See Fig. 3.) This feed-hopper *H* is formed or provided at a level some distance below its upper edge with an annular flange-like projection, which constitutes a circular track that rests and travels (as will be presently explained) on a series of small wheels *s*, which have their axes 125 suitably mounted in stationary journal-boxes arranged on the upper surface of the top plate of the furnace and just above said annular 130 flange or track. The said feed-hopper is provided with a toothed rim, with the teeth of

which engage the links of a drive-chain *l*. This chain is banded from said toothed rim to a small sprocket-wheel *m* on the lower portion of a vertical shaft *J*, that is stepped at its 5 lower extremity in a suitable bearing, as shown, and that near its upper end runs in a journal-box *w*, secured to the frame-work *B*.

As heretofore remarked with reference to the arrangement of track and wheels used in 10 connection with the turn-table, the similar arrangement of track and wheels used in connection with the feed-hopper *H* involves the advantage already explained of an avoidance of any undue collection of coal dust and dirt 15 on the surface of the track that would impede or interfere with the free action of the rotatory hopper. As already explained, it is the inverted position of the track relatively to the wheels which is the pith of my improvement 20 in this direction, and it is of course immaterial whether the location of this peculiar arrangement of circular track and wheels be precisely such relatively to the hopper as is shown in the drawings or be somewhat different 25 ent.

The upper end of shaft *J* carries a fast bevel-gear *i*, with which engages a similar gear *h* on one end of a short drive-shaft that is arranged within a bearing-box or casting 30 *G*, bolted to the upper portion of one set of legs of the duplex **A**-frame, and that has keyed on its other end the rope-wheel *E*, over which travels the cable *f*².

It will be seen that in a contrivance made 35 as shown at Sheet 2 and thus far described every time the skip-car *D* travels in one direction the rotation of the rope-wheel *E* through the medium of its shaft and the bevel-gear *h* causes the rotation of the sprocket-pinion *m* through the medium of the shaft *J* and gear *i*, and that by this rotation of the said pinion *m* the drive-chain *l* is made to turn or rotate the feed-hopper *H* a certain portion of one revolution. As the shaft *J* is 40 rotated in first one and then the other direction, (during the back-and-forth traveling movement of the skip-car on its track,) the pinion *m* is mounted to turn on the said shaft, but is connected therewith through the medium 45 of a pawl or pawls *p*, that engage with a ratchet *o* of said pinion, and that are pivoted to a fast collar *f*² (see Figs. 6 and 7) of said shaft, so that the hopper *H* is turned on its vertical axis of motion only when the shaft 50 *J* rotates in a given direction. In the case shown the relative sizes of the elements of the drive-gearing are such that the hopper at each movement turns less than one-third of a whole revolution and according to the diagram given 55 at Fig. 5—that is, starting with the nozzle *f*² in the position seen at Figs. 3 and 5 the first movement of the hopper *H* brings its discharge-nozzle to the point 2, the next movement to No. 3, the next to No. 4, and so on, under 60 which arrangement, it will be seen, the charges (such as seen at *x*, Fig. 3,) will be dumped at

the respective points, (shown at Fig. 5,) the three charges of each nearly complete rotation of the hopper overlapping each other, so to speak, all in such manner that in the aggregate of all the filling operations all the charges will be informally and continuously distributed in the most desirable predetermined manner. Of course some other subdivision of the complete rotation of the hopper may be made, and it may be arranged and driven so as to make the deposits of the successive charges closer together, more after the fashion of those which occur in the other type of furnace contrivance shown in Sheet 1. 70 80

As in the case of the form of apparatus shown in Sheet 1, the contrivance shown in Sheet 2 may be modified in many particulars without departing from my invention, so long as the revolving hopper (or some other device) is made to enforce the depositing of the successive charges brought up by the skip-car at different points, and so as to produce a perfect distribution evenly of the stock filled in to the furnace. 90

Without therefore limiting myself in carrying into effect my invention to any precise details of constructions or to the particular character of the devices applicable to one or the other of those two well-known and commonly-used types of blast-furnaces, which I have elected to show, what I claim, broadly, as of my invention, and desire to secure by Letters Patent, is— 95

1. The combination, with the top opening or openings of the furnace and suitable means or mechanism by which the successive charges of stock are conveyed from the stock-room to the furnace-top, of mechanism operating, as specified, to insure the depositing of said charges in succession at several different and predetermined points, and that is actuated in its successive operations in unison with the operations or movements of the said mechanism by which the charges of stock are carried up to the furnace-top, the said combination being substantially such as and operating in the manner hereinbefore more fully described. 100

2. In combination with the top opening of the furnace and suitable means for conveying to the vicinity thereof from the stock-room the successive charges of material to be fed to the furnace, a turn-table formed or provided with a suitable aperture for the ingress to the furnace of said charges of stock, and mechanism for rotating said turn-table automatically and in accordance with the action or operation of the mechanism by which the charges of stock are conveyed from the stock-room to the vicinity of the top opening of the furnace, all in substantially the manner and for the purposes hereinbefore set forth. 115 120 125

3. In combination with the furnace-top and a rotatory device for insuring or enforcing the entrance into the furnace of successive 130

charges of stock at different points, as specified, a circular track arranged at the under side of said rotatory device and traveling on top of a series of wheels by which it is supported and the axes of which are mounted in fixed bearings, all substantially in the manner and for the purposes hereinbefore set forth.

In witness whereof I have hereunto set my hand this 2d day of March, 1889.

ALEX. E. BROWN.

In presence of—

GEORGE C. WING,
H. F. BALCOM.
